UNITED STATES PATENT OFFICE.

ALLEN J. BECKER, OF ESSEX FELLS, NEW JERSEY.

CARBOY CARRIER.

Application filed April 14, 1921. Serial No. 461,884.

To all whom it may concern:

Be it known that I, ALLEN J. BECKER, a citizen of the United States, and a resident of Essex Fells, in the county of Essex and

5 State of New Jersey, have invented a new and Improved Carboy Carrier, of which the following is a full, clear, and exact description.

This invention relates to improvements in 10 carboy carriers of the general character set forth in my pending application, Serial Number 436,190, filed on January 10, 1921. In that application, I disclosed a carrier which could be used by two men to safely 15 transport one or more carboys.

The primary object of this invention is to provide a carrier which may be used by one man to conveniently transport carboys, and a carrier which will tightly grip a carboy 20 so that there is no danger of breakage and consequent injury to the carrying workman from the burning acid usually contained in such carboys.

A further object is to provide a carboy 25 carrier in the form of a truck, which will be capable of carrying carboys of various sizes, which will be simple and practical in construction, strong, durable and efficient in use, and comparatively inexpensive to manufacture.

30 With these and other objects in view, the invention consists in certain novel features of construction and combinations and arrangements of parts, as will be more fully 35 hereinafter described and pointed out in the claims.

In the accompanying drawings:—

Figure 1 is a perspective view illustrating 40 my improved carboy carrier in use,

Figure 2 is an enlarged view in transverse section on the line 2—2 of Figure 1,

Figure 3 is a fragmentary top plan view of the locking mechanism,

Figure 4 is a view in transverse section on 45 the line 4—4 of Figure 1,

Figure 5 is a similar view illustrating the parts in position to accommodate a larger carboy, and

Figure 6 is a fragmentary view in section 50 on the line 6—6 of Figure 4.

Referring in detail to the drawings, I have illustrated in dotted lines at 1, a carboy, equipped with the conventional side rails 2 under which a lifting device is engageable 55 to transport the carboy.

3 represents the single traction wheel of

my improved carboy carrier. The wheel 3 is mounted on an axle such as 4, and to this axle are attached the ends of side rails in a manner to be hereinafter described.

60

5, 5 represent the side rails of the carrier. These rails are of any suitable material, preferably a strong wood. Metal strips 7 are secured to the under faces of the forward ends of the rails and are bent to form hook shaped bearing sleeves 8 receiving the wheel axle 4. Spacing sleeves 9 are located around the axle 4 between the hub 10 of the wheel and the hooks 8. Adjusting sleeves 11 around the axle 4 are located between the 70 hooks 8 and nuts 14 on the ends of the axle, which retain all of the sleeves in position. These nuts are formed with diametrically opposed openings registering with transverse bores in the axle and pins 15 passed through 75 the openings serve to retain the nuts in place. These nuts can be removed to permit the interchanging of the positions of the hooks 8 and adjusting sleeves 11 so that the rails 5 may accommodate a larger carboy 80 between them, as indicated in Figure 5. Pins 16 passed through the intermediate portions of the strip 7 and the extremities of the hooks 8 prevent radial movement of the hooks relative to the axle.

85

The connection which the strips 7 afford between the rear axle and the rails 5 is necessarily somewhat flexible so that the rails may be spread apart and slipped over the top of a carboy and then advanced toward 90 one another to engage under the rails 2 of the carboy.

95

Angle brackets 17 secured to the inner faces of the rails 5 adjacent their forward ends prevent a carboy from sliding forwardly when the truck is in tilted position for wheeling.

100

The rails 5 terminate in any approved form of handle members 18 and adjacent the handle members, I provide an improved mechanism for positively preventing accidental spreading of the rails when a carboy is supported therebetween. This mechanism is somewhat similar to the one illustrated in my pending application above referred to, but embodies various novel features which will appear in the following description.

105

A relatively long metal arm 19 and a relatively short metal arm 20 are secured to the rails 5 adjacent the handle members 110 and extend inwardly. These arms are angular in shape at their outer ends and embrace

the rails 5. Triangular webs or plates 21 are held against the under faces of the rails 5 by strengthening braces in the form of metal strips 22 and securing devices 5 such as the bolts 23 are utilized to clamp the arms 19 and 20, plates 21 and braces 22 to the rails. That brace 22 which is associated with the shorter arm 20 extends well under the arm 19 and is movable through 10 depending rectangular guide brackets 24 carried by the arm 19. A ratchet 25 is supported upon the arm 19. An offset spring arm 26 attached to the arm 20 carries a dog 27 maintained in engagement with the 15 ratchet by the resiliency of the arm 26. This dog is integral with a loop handle member 28 for manually lifting the same out of engagement with the ratchet. A rectangular guide bracket 29 fixed to the 20 longer brace 22 is passed through the handle member 28 and encircles the arm 19 and the ratchet 25.

The ratchet and dog arrangement above described, permits the rails to be quickly 25 advanced toward one another to tightly grip under a carboy, as seen in Figure 1, but positively prevents accidental spreading of the rails.

It has been noted before that the connection 30 between the rails 5 and the axle 4 lends sufficient flexibility to the construction to permit such spreading. After the rails have been passed around the carboy and under the rails 2, the handles 18 are raised and the 35 device functions as a one-man truck which may be used to wheel a carboy.

Although I have illustrated one of the 40 preferred embodiments of my invention, it will be apparent that various slight changes and alterations might be made in the general form and arrangement of the parts described without departing from the invention and hence I do not wish to limit myself to the precise details set forth, but 45 shall consider myself at liberty to make such slight changes and alterations as fairly fall within the spirit and scope of the appended claims.

It might be noted that the carboy is further 50 positively held against movement in the carrier by inwardly presented pointed pins or spurs 30 carried by the inner faces of the rails 5 and engageable in the soft wood of the carboy as the rails are pressed 55 against the sides thereof.

I claim:

1. A carboy carrying truck including a traction wheel, a wheel axle extending laterally on each side of the wheel, a pair 50 of rails adapted to support a carboy be-

tween them, metal strips attached to the forward ends of the rails, said strips including hook shaped bearing sleeves receiving the wheel axle, pins passed through the intermediate portion of the metal strips and 65 through the extremities of the hooks, whereby the strips are held against radial movement relative to the axle.

2. A carboy carrying truck including a traction wheel, a wheel axle extending 70 laterally on each side of the wheel, a pair of rails adapted to support a carboy between them, metal strips attached to the forward ends of the rails, said strips including hook shaped bearing sleeves receiving 75 the wheel axle, a plurality of spacing sleeves around the wheel axle, and means permitting the interchanging of the positions of the hook shaped members and certain of the spacing sleeves, whereby various sized 80 carboys may be supported between the rails.

3. A carboy carrying truck including a traction wheel, a wheel axle extending laterally on each side of the wheel, a pair 85 of rails pivotally secured to the axle and adapted to support a carboy between them, a ratchet toothed bar and a spring held dog carried by the opposite rails permitting the advance of the free ends of the rails toward each other and preventing their relative separation.

4. A carboy carrying truck including a traction wheel, a wheel axle extending laterally on each side of the wheel, a pair 90 of rails pivotally secured to the axle and adapted to support a carboy between them, a ratchet toothed bar and a spring held dog carried by the opposite rails permitting the advance of the free ends of the rails toward each other and preventing 100 their relative separation, and a looped handle member integral with the dog for lifting said dog out of engagement with the ratchet teeth.

5. A carboy carrying truck including a 105 traction wheel, a wheel axle extending laterally on each side of the wheel, a pair of rails pivotally secured to the axle and adapted to support a carboy between them, a ratchet toothed bar and a spring held dog 110 carried by the opposite rails permitting the advance of the free ends of the rails toward each other and preventing their relative separation, a looped handle member integral with the dog for manually lifting 115 the dog out of engagement with the ratchet teeth, and means limiting the relative separation of the rails.

ALLEN J. BECKER.
